INVENTOR:

LEWIS WILLIAMS,

by Franklin Scott, Atty.

UNITED STATES PATENT OFFICE.

LEWIS WILLIAMS, OF JOHNSTOWN, PENNSYLVANIA.

BALE-TIE.

SPECIFICATION forming part of Letters Patent No. 295,819, dated March 18, 1884.

Application filed January 30, 1884. (No model.)

To all whom it may concern:

Be it known that I, LEWIS WILLIAMS, of Johnstown, in the county of Cambria and State of Pennsylvania, have invented certain 5 Improvements in Bale-Ties, of which the following description, in connection with the accompanying sheet of drawings, constitutes a specification.

The device constituting the subject-matter 10 of this invention is designed to be used as a fastening in cases where wire is employed in baling hay, cotton, rags, and analogous articles; and it consists of a single link of peculiar 15 form or construction, which constitutes the only appliance whereby the opposing ends of the baling-wire are united and confined.

The nature of the invention is fully exemplified in the drawings, in which different 20 modifications of the binding-link are shown in 25 Figs. 1, 4, and 5, and its application and mode of use are seen in Figs. 2 and 3.

I preferably make the binding-link of wire, 25 as seen in Fig. 1, although it may be struck up from plate metal, as in Fig. 4, or cast solid, as 30 in Fig. 5. All these different styles embody 35 the same essentials, which are a relatively long or oblong loop or eye, *c*, formed at one end of the link, and a substantially circular transverse perforation, loop, or eye, *a*, at the other end, 40 said eyes being so arranged that the axis of their openings shall be transverse to each other.

The link shown in Fig. 1 may be made by bending the opposite ends of a short piece of wire around at right angles, but in opposite 45 directions, so as to form the lips *b* and *d*, and then bending or reflecting one end of the wire 50 backwardly until lip *b* rests across the main body of the wire, after which the opposite end of the wire is bent inwardly over lip *b* at or near its end, so that lip *d* may rest upon the body of the wire a little back of the angle formed by bending lip *b*, as seen in the figure. This manipulation of the wire will thus form a long loop, *c*, and the included interval between lips *b* and *d* will constitute a substantially 55 circular or closed round eye or loop large enough to freely admit the insertion of the end of the baling-wire, as will be hereinafter more fully described. It will be seen that the 60 axis of eye *a* is practically parallel with the plane of loop *c*; or, in other words, the axes

of the eye and loop are transverse with each other. The two lips *b* and *d* are arranged, as shown, so as to favor bending the inserted end of the baling-wire across one of them as a fulcrum without distorting or straightening out the link. 55

The eyes *a a* and loops *c c* shown in Figs. 4 and 5 present like characteristics and are used in precisely the same way as the eye and loop seen in Fig. 1, and therefore I make no further description of them. 60

My improved link is used as follows: While the pressed bale of material is still in the press, the binding-wires lying in position for their 65 ends to be seized, one end of the band—as, for instance B—is passed through loop *c*, bent back, and twisted about the body of the main wire, as seen in Figs. 2 and 3. Link A is then doubled back, as shown in Fig. 2, and while 70 in this position the other end of the wire band C is brought around, and its end *e* is passed through loop *c*, eye *a*, and also through loop *g*, the several parts thus being in positions 75 shown in Fig. 2. At this stage the protruding end *e* is bent backwardly across lip *d* over to about a right angle, or as shown by the dotted lines. At this point pressure on the bale is removed, when the expansive strain of the 80 bound material causes the opposed ends of the band to recede from each other, and this separation causes link A to "turn over" or change 85 ends, which operation results in causing the end *e* to be again bent athwart lip *b* of the link A, so as to become cranked, as shown in Fig. 3, the end of the band *e* being held or confined in loop *g*.

By the foregoing described means the end *e* of the wire band is cranked when it passes through eye *a*, and is prevented from being 90 bent around, so it can be withdrawn through said eye by confinement in loop *g* in such a way that no ordinary strain brought to bear on the band can so loosen the tie as to effect a rupture thereof, or such a weakening as to 95 lead to its separation.

I claim as my invention—

1. The described bale-tie, consisting of a link having one end formed as an oblong open loop for receiving and retaining one end of the baling-wire, and the opposite end thereof provided with an eye, of which the axis is sub- 100

stantially parallel with the plane of the said oblong loop, but lies transversely therewith, the walls of said eye constituting abutments or shoulders over which the other inserted end 5 of the baling-wire is bent or cranked, substantially in the manner described, and for the purposes set forth.

2. A link for uniting and fastening the ends 10 of wire bale-bands, having the described loop and eye, relatively arranged and disposed substantially as shown, made from wire bent into the form described, substantially as specified.

3. The method shown of fastening the ends 15 of a wire bale-band, which consists in connecting one end of the band by means of a loop with the loop end of the described connecting-link, doubling said connecting-link back upon the loop of the band, inserting the other end 20 of the band endwise through the loop end of the connecting-link, then through the eye thereof, and also through the loop at the other end of the bale-band, substantially as shown, and bending the protruding end of the wire so inserted back to about a right angle, as de-

scribed, and finally distending the band, so as 25 to cause the said connecting-link to turn over or reverse its position endwise, whereby said inserted end of the bale-wire is cranked, in the manner described, and for the purposes set forth.

4. The described bale-tie, consisting of a wire bale-band having one end thereof connected by a loop with the loop end of the described connecting-link, and its other end passed through the eye of said link and confined within the loop at the opposite end of the band, said band-wire being cranked or bent at a transverse angle upon itself at the point where it traverses the eye of the connecting-link, substantially as described and set 30 35 forth.

In testimony whereof I have hereunto subscribed my name, at Johnstown, Pennsylvania, this 15th day of January, A. D. 1884.

LEWIS WILLIAMS.
In presence of—
JNO. L. ROYER,
G. W. MAPLEDORANE.
